HINGE

Joseph Soss, Roselle, N. J.

Application July 22, 1937, Serial No. 154,943

7 Claims. (Cl. 16—163)

This invention relates to hinges and particularly to devices of this kind designed for use in supporting the lift doors or closures of trunk or luggage compartments of motor vehicles, and the object of the invention is to provide a hinge of the class described wherein a comparatively wide throw of the swinging member or closure is provided, and further wherein the closure will be drawn into its closed position by the linkage provided in the hinge while at the same time permitting a free swinging movement in the operation of moving the door or closure into open position; a further object being to provide a hinge consisting of two butt parts coupled together by straight and hook-shaped links wherein one of the butt parts is in the form of a hook-shaped body normally enveloping a part of the other butt, both of the butt parts having link supporting portions arranged in spaced relation to the attaching plates of said butt parts and the supports to which they are attached; a still further object being to so construct one of the butts of the hinge, namely the hook-shaped butt so as to clear a projecting drain trough or channel disposed between adjacent edges of the stationary support and swinging member in the operation of moving the swinging member into open position, and with these and other objects in view, the invention consists in a hinge of the class and for the purpose specified which is simple in construction, efficient in use and which is constructed as hereinafter described and claimed.

The invention is fully disclosed in the following specification, of which the accompanying drawing forms a part, in which the separate parts of my improvement are designated by suitable reference characters in each of the views, and in which:

Fig. 1 is a longitudinal sectional view through a hinge made according to my invention illustrating the method of its use.

Fig. 2 is a section substantially on the irregular line 2—2 of Fig. 1.

Fig. 3 is a view similar to Fig. 1 showing a modification.

Fig. 4 is a section substantially on the irregular line 4—4 of Fig. 3, and omitting a part of the construction and

Fig. 5 is a section on the broken line 5—5 of Fig. 3.

In Fig. 1 of the drawing I have indicated at 5 a part of the body of a motor vehicle, and at 6 part of the closure or cover for a trunk or luggage compartment of such vehicle. At 7 is

shown a trough or channel secured to the body upon and disposed between adjacent abutting edges 8 of the parts 5 and 6 to collect water that may pass between said abutting edges as in other devices of this kind. The hinge shown in Figs. 1 and 2 consists of a butt part 9 and butt part 10. The part 9 has angularly extending bearing plates 11 which extend to one side of the attaching plate portions 12 thereof, the latter being indicated by dotted lines in Fig. 2 of the drawing, the bearing plates 11 being joined by a connecting wall 13 which extends from the attaching plates 12 to a point inwardly of the free end of said bearing plates.

The butt 10 consists of a hook-shaped arm 14 which is U-shaped or channel-shaped in cross sectional form, the top and bottom or in other words side walls 15 of the arm 14 forming bearing plates to which links 16 and 17 are pivoted as seen at 18 and 19, said links being also pivoted to the bearing plates 11 of the body 9 as seen at 20 and 21.

The links 16 and 17 in the construction shown are composed of sheet metal, the link 16 being straight and the link 17 hook-shaped in form, but it will be understood that these links as well as the butts 9 and 10 may be constructed in any desired manner, that is to say of castings or forgings, it being understood that the links 16 and 17 may also be formed from rolled sections.

The butt 10 includes at the wide end of the hook-shaped arm 14 laterally extending attaching plates 22 by means of which said butt may be attached to the swinging support 6. It will be understood that in hanging or mounting the closure 6 of the type and kind defined a pair of the hinge units shown may be employed, one preferably at each side portion of the closure, and that both hinge units may be of the same structure. Only one of such hinges are shown in order to simplify the illustration.

One of the distinctive features of my invention is to provide a hinge for the purpose specified that will be strong and durable in construction and at the same time of economical structure so as to reduce the cost of manufacture thereof. It will also be understood that by providing the hook arm 14 on the butt part 10, this arm extends the butt part 10 to a point beneath as well as in close proximity to the bearing plates 11 of the butt 9 so that relatively short links may be employed. At the same time this hook arm serves to clear the drain trough or channel 7 when the closure 6 is swung into open posi-

tion in the manner indicated by dotted lines in Fig. 1.

In the construction shown in Figs. 1 and 2, the links 16 and 17 are of such width as to fill the space between the bearing plates or walls 11, 15 of the respective butt parts, said bearing plates or walls being in the same alinement thus permitting the use of links of the same width throughout, clearly to be seen upon a consideration of Fig. 2 of the drawing.

In Figs. 3, 4, and 5, of the drawing I have shown a slight modification of the structure shown in Figs. 1 and 2, wherein the links 16a and 17a are of laminated construction, or in other words, which consists of two or more separate sheet metal parts arranged one upon the other. The butt part 9a has its bearing plates or arms 11a disposed in closer arrangement to each other than in Fig. 2 as is also true of the hook arm 14a of the butt part 10a. It will be understood that any spacing may be provided between the bearing plates and a greater or lesser number of the laminations provided in the links 16a and 17a.

Aside from the size of the parts 9a, 10a, and the use of the laminated links 16a, 17a, the structure shown in Figs. 3, 4, and 5 will operate in the same manner as the structure shown in the other figures. It will be understood that the separate parts of the links 16a, 17a, may be welded or otherwise secured together.

It will be understood that the illustration in the accompanying drawing is simply to designate possible arrangements and construction of the hinge parts, it being apparent that the contour of the butt parts and the links may be modified to suit other mountings and uses of the hinge.

With the construction shown it will be understood that as the closure 6 is moved from its closed position, the linkage between the butts 9 and 10 will cause the closure to first move to the right, as viewed in Fig. 1, and at the same time swing upwardly and outwardly through a relatively wide arc producing what may be termed a wide throw hinge. The initial movement to the right provides free release of the closure from its support while at the same time, in moving the closure into its closed position, a more perfect seating or nesting of the closure in the support is provided by reason of the movement to the left which tends to bring the abutting edges as at 8 into close engagement with each other.

With the linkage construction employed, it will be apparent that the free end of the hook-shaped arm 14 swings in a true arc governed by the straight link 16 whereas the remainder of the butt swings in an irregular arc which causes the hook-shaped link 17 to move from the position shown in full lines to a position within the channel of the hook-shaped arm as indicated in dotted lines in swinging the hinge from the closed to the open position. This construction produces the outward throw and outward swing of the closure as will be apparent. It will also be understood that the hinge will assume a substantial self-sustaining position when in open position by virtue of the arrangement of the links between the respective butts. When the swinging member or door is in closed position, the link 17 or the offset portion thereof will engage the link 16 adjacent the pivot 20 and prevent rattling or relative movement of said butt.

It will be understood that the operations of the hinge shown in Figs. 1 and 2 above referred to are also true with regard to the structure

shown in Figs. 3, 4, and 5. It will also appear that the several parts of the hinge may be made in any desired manner, the sheet metal parts herein shown being merely illustrative of one of the several types and methods of constructing the hinge.

Having fully described my invention what I claim as new and desire to secure by Letters Patent, is:

1. A motor vehicle hinge for use in supporting the door or closure of a trunk compartment in connection with the body of a vehicle, said hinge comprising a butt secured to the vehicle body, another butt secured to the closure, both butts having attaching plate portions arranged substantially in the same plane, the attachment of the butt to said closure being in widely spaced relation to said vehicle body, the last mentioned butt being provided with a hook-shaped arm extending in the direction of and overlapping the first named butt, links pivotally coupled with the first and second named butts, in that section or area thereof which overlap, the free end of the hook-shaped arm joining the central portion of the first named butt in a straight link, and the free end of the first named butt joining the hook-shaped arm inwardly of the free end thereof with a hook-shaped link, to provide swinging movement of said arm through an arc-shaped path in the operation of moving the closure from a closed to an open position.

2. A hinge of the class described comprising two butts, each butt having attaching plate portions, a hollow hook-shaped arm projecting to one side of the attaching plate portion of one butt in the direction of the opposed butt, said opposed butt having a substantially straight arm extending angularly from the attaching plate portion thereof and being channel-shaped in cross sectional form, the free end portion of the arm of the second named butt nesting within the hook-shaped arm of the first named butt when said butts are in closed position, and a pair of links hingedly coupling the arms of both butts, with one end of each link pivoted to the free end of the respective arms.

3. A hinge of the class described comprising two butts, each butt having attaching plate portions, a hollow hook-shaped arm projecting to one side of the attaching plate portion of one butt in the direction of the opposed butt, said opposed butt having a substantially straight arm extending angularly from the attaching plate portion thereof and being channel-shaped in cross sectional form, the free end portion of the arm of the second named butt nesting within the hook-shaped arm of the first named butt when said butts are in closed position, a pair of links hingedly coupling the arms of both butts, and one of said links being straight and extending between the free end of the hook-shaped arm and the central portion of said channelled arm to guide the free end of the hook-shaped arm through a true arc with respect to said channelled arm.

4. A hinge of the class described comprising two butts, each butt having attaching plate portions, a hollow hook-shaped arm projecting to one side of the attaching plate portion of one butt in the direction of the opposed butt, said opposed butt having a substantially straight arm extending angularly from the attaching plate portion thereof and being channel-shaped in cross sectional form, the free end portion of the arm of the second named butt nesting within the hook-shaped

arm of the first named butt when said butts are in closed position, a pair of links hingedly coupling the arms of both butts, one of said links being straight and extending between the free end of the hook-shaped arm and the central portion of said channelled arm to guide the free end of the hook-shaped arm through a true arc with respect to said channelled arm, the other of said links being hook-shaped in form and pivoted to the free end of the channelled arm and to the hook-shaped arm inwardly of the free end thereof, and said hook-shaped link being adapted to seat within the hook-shaped arm when the hinge is in open position.

5 5. A hinge of the class described comprising two butts, each butt having attaching plate portions, a hollow hook-shaped arm projecting to one side of the attaching plate portion of one butt in the direction of the opposed butt, said opposed butt having a substantially straight arm extending angularly from the attaching plate portion thereof and being channel-shaped in cross sectional form, the free end portion of the arm of the second named butt nesting within the hook-shaped arm of the first named butt when said butts are in closed position, a pair of links hingedly coupling the arms of both butts, one of said links being straight and extending between the free end of the hook-shaped arm and the central portion of said channelled arm to guide the free end of the hook-shaped arm through a true arc with respect to said channelled arm, the other of said links being hook-shaped in form and pivoted to the free end of the channelled arm and to the hook-shaped arm inwardly of the free end thereof, said hook-shaped link being adapted to seat within the hook-shaped arm when the hinge is in

open position, and said hook-shaped link being adapted to engage the straight link when the hinge is in closed position.

6. A concealed hinge attachable to the inner surfaces of a support and a swinging member, comprising butt parts having attaching plates secured to said inner surfaces, said plates and inner surfaces being respectively arranged, in the closed position of the hinge, in common alignment, said plates having angularly extending arms extending in the direction of the intersection between the support and swinging member and overlapping each other, the arm of the butt attached to said swinging member being hook-shaped in form, and the overlapped portions of 15 said arms being coupled together by a pair of links pivoted to each arm and disposed between adjacent overlapped surfaces of said arms.

7. A concealed hinge attachable to the inner surfaces of a support and a swinging member, 20 comprising butt parts having attaching plates secured to said inner surfaces, said plates and inner surfaces being respectively arranged, in the closed position of the hinge, in common alignment, said plates having angularly extending 25 arms extending in the direction of the intersection between the support and swinging member and overlapping each other, the arm of the butt attached to said swinging member being hook-shaped in form, the overlapped portions of 30 said arms being coupled together by a pair of links pivoted to each arm and disposed between adjacent overlapped surfaces of said arms, said arms being of channelled cross sectional form, and the side walls of the channels of said arms 35 being in common alignment.

JOSEPH SOSS.
